UNITED STATES PATENT OFFICE.

ANNA D. ROSTOW, OF NEWARK, NEW JERSEY.

DEVICE FOR SHAPING NOSES.

1,100,991.

Specification of Letters Patent. Patented June 23, 1914.

Application filed January 28, 1914. Serial No. 814,851.

To all whom it may concern:

Be it known that I, ANNA D. ROSTOW, citizen of the United States of America, residing at Newark, in the county of Essex 5 and State of New Jersey, have invented certain new and useful Improvements in Devices for Shaping Noses, of which the following is a specification.

Most children are born, and many grow 10 up with flat, long, up-turned, one-sided noses or those with narrow or distended nostrils, which not only disfigure the appearance of the face, but prevent good breathing.

Experience has shown that occasional gentle pressure around a deformed nose frequently suffices to remedy the deformities. 15 With this fact in mind, I have designed a device, whereby by a continuous gentle pressure exerted on a deformed nose, the restoration 20 of the latter to normal shape will be more successfully brought about.

My invention consists in the combination, arrangement and construction of parts, as will be hereinafter fully set forth in the annexed claims.

In the accompanying drawing, in which similar reference characters denote corresponding parts, Figure 1 shows my new device in use; Fig. 2 is an enlarged top plan view thereof; Fig. 3 is a cross section on line 3—3 of Fig. 1; Fig. 4 is a front elevation of the middle and lower portion of the device; Fig. 5 is a longitudinal section of the device on line 5—5 of Fig. 3; Fig. 6 is a sectional view of a modified form; Fig. 7 is a perspective view of another modified form; Fig. 8 is a cross section on line 8—8 of Fig. 7 and Fig. 9 is a detail.

The new device substantially consists of a 40 frame or form made of suitable light weight and porous or perforated material, which is cut out into suitable shape and bent to conform with the shape of a normal nose. In use the frame or body portion is adapted to 45 be placed over the deformed nose, so as to envelop the same entirely from the bridge portion of the cartilage and bottom thereof. The edges of the frame are stiffened by 50 resilient means, such as wires or the like, which are adapted to keep the body or frame in its shape and also to exert continuous but gen-

tle pressure on the fleshy part of the nose. Such continuous pressure mainly will have the effect not only to gradually transform the nose into normal shape, but also by raising the flesh at some parts and compressing it at other parts, as determined by the shape of the frame, to improve breathing. Thus for instance a flat nose bridge will prevent good respiration, as the soft part of the 60 bridge rests on the superior turbinate, and frequently upon both the superior and middle turbinate. By the continuous and gentle pressure upon the deformed part the frame will, in raising the soft part, bring 65 the former into normal shape and improve the respiration.

In case of closed nostrils, respiration is very difficult. To remedy this deformity, I provide either short tubes *i* of celluloid or 70 other suitable material, which I attach to the inner part of the frame, as shown in Figs. 1, 3, 5 and 6. These tubes are open at the top and bottom and have side respiration openings *i'*, and serve the purpose to 75 spread the nostrils. Instead of such tubes, coils *k* (Fig. 9) of celluloid or other suitable material may be used.

According to the construction shown in Fig. 3, the frame or body is composed of two 80 different pieces of soft and porous material, the outer part *a'* being preferably of canvas and the inner part *a''* of lawn or the like to serve as lining. Each piece of material is cut, so that when subsequently bent upon 85 itself to the shape of a nose, will form side pieces *a^b*, which toward the lower ends increase in width, as at *a^b*, to cover the outer side walls of the nostrils, and a tongue-shaped piece *a^c* which will extend below the 90 cartilage. The two pieces of material are united, by placing the lining on top of the canvas, stitching the former to the latter first along its longitudinal central line and stretching or drawing it tightly lengthwise 95 at the lower end, then stitching them at the sides. After bending the two pieces upon themselves, the lining is drawn tightly side-wise to give the shape. Around the edges of the bent form are then attached resilient 100 means, such as wires *a^d* which stiffen or reinforce the form and which serve as the

means whereby the desired pressure on the nose is obtained. The wires a^3 are inclosed in a piece of material a^4 stitched around the edges of the form or frame. For bigger or 5 adults' noses, three thin wires woven in a tape may be used. For smaller or children's noses, two such wires are sufficient and for still smaller or infants' noses, a single wire may be used.

- 10 The form or frame may be made of different sizes and weight to correspond with differently sized noses. It also may be made of canvas b only as shown in Fig. 6 or of celluloid c which is perforated throughout 15 its entire surface as at c' (see Figs. 7 and 8). When the frame is made of material such as celluloid, as in Fig. 6, the stiffening or reinforcing effect is produced by curving its lateral edges c^2 upwardly or outwardly. 20 The side flaps are held together by a cross piece c^3 . The tongue piece a^5 which is adapted to rest against the bottom of the nose serves to press upon the cartilage between the nostrils and to thereby impart to 25 the bottom of the nose a normal shape.

As auxiliary means for securing the bent form or frame in the given shape, I provide a cross piece h of tape or the like, which is applied to the lower part of the nose to extend 30 across the tongue a^6 and to be suitably fixed to the side flaps as at g , either by stitching or by press buttons. This cross piece prevents the side flaps from spreading apart.

- 35 To hold the form in place different means may be used. Thus, if the form is made of celluloid, the same is formed with curved or bent strips or ear pieces d of metal, celluloid or other suitable material, which are 40 adapted to be passed around and engage the back of the ears. These ear pieces must be covered with tape or other soft material so as to avoid injury to and undue pressure on the wearer. Another and more satisfactory 45 means for attaching the form and maintaining it in proper position consists of a frame e of wire having the shape of spectacles. This frame differs from ordinary eyeglass frames in that its bridge portion is made 50 higher and narrower and is so connected to the oval parts that the latter fit closely to the face. Furthermore, the oval parts are bent inwardly at the sides, as shown in Fig. 2, so that the same, too, may rest against 55 the parts of the face around the eyes. By such structure the form applied to the nose will be prevented from being removed or displaced, while the wearer is lying on the side. To the ends of the 60 oval parts of the frame e are suitably secured short strips f of metal, celluloid or the like, which are covered with tape or other soft material and to which are se-

cured bands f' of tape to be passed around the ears and tied below the chin. In addition there may be bands h' stitched to the side parts of the form or to the cross piece h , and which are adapted to be passed around the cheeks and tied at the back. By these bands h' the position of the form on 70 the nose will be still more insured.

Since various other modifications may be made in the construction of my device without deviating from the principle of my invention, I do not wish to restrict myself to 75 the details shown and described.

What I claim and desire to secure by Letters Patent is:

1. A nose shaper, comprising a body portion of light weight and porous material 80 bent into the shape of a normal nose and having stiffened edges, the stiffened edges serving to maintain the form in shape and to exert gentle and continuous pressure on the parts of a deformed nose. 85

2. A nose shaper, comprising a body portion of light weight and porous material bent into the shape of a normal nose and serving to envelop the latter entirely, stiffening means attached around all the edges of 90 said body and serving to preserve the shape of the latter and to exert continuous gentle pressure on the same and means for attaching said body to the face of the wearer.

3. A nose shaper, comprising a body portion of light weight porous material having resilient stiffening members around its edges, the body portions being bent in form of a normal nose, said members serving to hold said body in shape and to impart continuous gentle pressure on the nose and means in the lower inner part of the body adapted to be inserted into the nostrils of 100 the nose to spread them apart. 95

4. A nose shaper, comprising a body portion of light weight and porous material bent into the form of a normal nose and being stiffened at its edges, a cross piece extending across the bottom of the said body 105 to hold the lateral parts together and means 110 for attaching said body to the face of the wearer.

5. A nose shaper, comprising a body portion of light weight and porous material bent into the form of a normal nose and being 115 stiffened at its edges, a frame shaped in form of an eyeglass frame attached to said body and bands connected to said frame to be tied around the head of the wearer.

6. A nose shaper, comprising a body portion of light weight and porous material bent into the form of a normal nose and being stiffened at its edges, a frame shaped in form of an eyeglass frame attached to said body and bands connected to the lower parts 120 125 of the side pieces of said body and adapted

to be tied around the head so as to secure
the shaper in proper position.

7. A nose shaper, comprising a body portion bent into the shape of a normal nose
5 and means in said body portion adapted to
be inserted into the nostrils of the nose to
spread them apart.

In testimony whereof I affix my signature
in presence of two witnesses.
